[57] CLAIM

The ornamental design for a seat, as shown and described.

DESCRIPTION

FIG. 1 is a front, left side perspective view of a seat showing my new design;

FIG. 2 is a front elevational view thereof;

FIG. 3 is a left side perspective view thereof with the right side perspective view being a mirror image thereof;

FIG. 4 is a rear perspective view thereof;

FIG. 5 is a top plan view thereof;

FIG. 6 is a front, left side perspective view of a second embodiment of the seat;

FIG. 7 is a front elevational view of said second embodiment;

FIG. 8 is a left side perspective view of said second embodiment, with the right side perspective view being a mirror image thereof;

FIG. 9 is a rear perspective view of said second embodiment; and,

FIG. 10 is a top plan view of said embodiment.
